(57) **CLAIM**

The ornamental design for a wall-mounted touch panel, as shown and described.

DESCRIPTION

FIG. 1 shows a front right isometric view of the wall-mounted touch panel.

FIG. 2 shows a back left isometric view of the wall-mounted touch panel.

FIG. 3 shows a front elevation view of the wall-mounted touch panel.

FIG. 4 shows a top plan view of the wall-mounted touch panel.

FIG. 5 shows a bottom plan view of the wall-mounted touch panel.

FIG. 6 shows a right elevation view of the wall-mounted touch panel; and,

FIG. 7 shows a back elevation view of the wall-mounted touch panel.

The broken lines shown in the drawings are directed to unclaimed portions of the article and are for informational purposes only and form no part of the claimed design.
